Patented Mar. 31, 1925.

UNITED STATES PATENT OFFICE.

MARK F. POSTLEWAITE AND TROY V. LAWSON, OF SAN ANTONIO, TEXAS.

PIPE COIL FOR USE IN REFRIGERATION SYSTEMS.

Application filed April 18, 1923. Serial No. 632,926.

To all whom it may concern:

Be it known that we, MARK F. POSTLEWAITE and TROY V. LAWSON, citizens of the United States, residing at San Antonio, in the county of Bexar and State of Texas, have invented certain new and useful Improvements in Pipe Coils for Use in Refrigeration Systems, of which the following is a specification.

Our invention relates to improvements in pipe coils and more particularly to pipe coils for use in refrigeration systems, although we do not wish to be limited to this particular use.

One of the primary objects of the invention is to provide a pipe coil for refrigeration systems which is especially adapted either for use in a freezing tank, as a condenser coil, or as a direct expansion coil.

A further object of the invention is to provide a pipe coil of the above described character which, when installed in the freezing tank, makes possible the installation of a materially greater evaporating surface than is possible with any other type of pipe coil now in use, and which evaporates the maximum amount of ammonia per square foot of surface at a minimum difference in temperature.

A further object of the invention is to provide a pipe coil for use in a freezing tank which permits of the removal of the ammonia gas at minimum velocities.

A further object of the invention is to provide a coil of the above described character for use in freezing tanks which can be made of suitable size and shape to fit any size tank, and which is adapted to be assembled therein without the use of screw or packed joints.

A further object of this invention is to provide a pipe coil for use as above described, which eliminates the possibility of breakage by the ice cans, which breakage causes the loss of a large part of the charge of ammonia. This coil additionally provides supports for the frame work and can covers of the tank and requires no extra support for itself.

Other objects will be in part obvious from the annexed drawings and in part indicated from the following analysis of the invention.

The invention accordingly consists in the features of construction, combination of parts, and in the unique relation of the various members and the relative propor-

tioning and dispositioning thereof, all as more clearly outlined herein.

To enable others skilled in the art to fully comprehend the underlying features thereof, in order that they may embody the same, by numerous modifications in structure and relation contemplated by this invention, drawings depicting the preferred forms have been annexed as part of this disclosure and in such drawings like characters of reference indicate corresponding parts throughout all the views, of which—

Figure 1 is a side elevation of a part of a preferred form of coil arrangement;

Figure 2 is a detail of a preferred form of joint; and

Figure 3 is a partial plan view of the freezing tank and refrigerating sections thereof; and

Figure 4 is a perspective of the coil when used as a condenser coil.

Referring now to the drawings, wherein is shown our improved type of coil applied to a freezing tank, and more particularly to Figure 1, the numerals 10 and 11 indicate horizontal tubular headers positioned parallel to each other and spaced apart a distance suitable to the depth of the tank used. A series of parallel pipes 13 connect these tubular headers and are preferably arranged perpendicular thereto, although it is evident that the pipes 13 may be positioned at an angle greater or less than the vertical with respect to the aforesaid headers if desired.

Referring to Figure 2, the joints 14 of the headers and the vertical pipes are preferably formed by welding, either electric, oxy-acetylene or by butt welding, although it is evident that the headers and vertical pipes may be cast integrally. This type of connection forms in a refrigeration system a positive means of eliminating leakage of the ammonia gas with its very harmful effects to the system and inconvenience in attendance.

Referring now to Figure 3, wherein is shown the preferred arrangement in a freezing tank, a series of horizontal headers 16 and 17 are positioned longitudinally in a tank 15 which is substantially rectangular, as has been found practical in use, each series consisting of an upper and lower header in the same vertical plane. A number of sections of the pipe coils, as shown in Figure 1, comprising the horizontal

headers 10 and 11 and the vertical connecting pipes 13, are arranged in the tank at right angles to the longitudinal headers 16 and 17, the horizontal headers 10 and 11 being connected thereto and welded at the joints 18.

The joints 19 at the inlet and 20 at the discharge end of the tank, connecting these longitudinal headers with the rest of the system, are also preferably welded to eliminate, at this point, any leakage of ammonia gas. The liquid ammonia is fed into the end of the bottom headers opposite the gas outlet of the suction or top header. Sufficient ammonia liquid is fed into the coil to bring the liquid level approximately half way up the vertical pipes, in which pipes the liquid is evaporated and the resulting gas conveyed out of the tank and to the ammonia compressor by the upper horizontal headers. The ammonia gas thus circulating through the pipe coil abstracts heat from the cooling medium in the tank 15, which may be brine or calcium chloride, and the same is cooled to a degree necessary to freeze the water in ice cans placed in the compartments 21. It is evident that the above described arrangement of the horizontal headers and vertical connecting tubes presents an efficient and practical manner of evaporating the liquid ammonia to obtain the maximum capacity of the system.

The arrangement of vertical pipes has the further advantage of preventing the cans, when in the process of being inserted, from catching on the pipes and causing breakage thereof, as is very frequently the case when a horizontal coil is used.

As hereinbefore mentioned, the brine or calcium chloride freezing medium is kept in constant circulation by the brine agitators 22 and 23, forming a complete cycle thereof. The ammonia gas is let off from the discharge end of the coil back to the compressor and the cycle of operation is again commenced. It is also obvious that the arrangement as described with reference to the can system of indirect refrigeration might also be applied to a plate ice system and that such re-arrangement would require only a difference in design.

The peculiar arrangement of horizontal header and vertical tubes has been found by practice to be equally adaptable for use as a condenser coil and in a direct expansion system.

In Figure 4 is shown the preferred arrangement of this type of coil when used as a condenser. In this form of use, coils of the type shown in Figure 1 are preferably connected up in pairs, one coil being of standard height and the other being approximately one-half as high as its companion coil. The hot gas from the ammonia compressor enters the end of the top horizontal header 10

as at 24, is condensed, and the resulting liquid drops through the vertical pipes 13 to the bottom horizontal header 11, which is connected to the bottom header of the shorter or liquid cooling coil by the cross connector tube 25. The liquid is cooled in this shorter coil and taken out of the top header as at 26 to the liquid receiver. Water is distributed over both of these coils at the same temperature, in sufficient quantities to cool and liquefy the ammonia gas. As in the prior arrangements of coil described, the joints are all preferably welded.

With the direct expansion system, the welded or cast joints present materially greater advantages than types of coils in which the joints are packed or screw joints. The use to which this direct expansion system is usually put, namely, the cooling of storage rooms, necessitates a positively leakage-proof system, and our proposed type of coil is one which is peculiarly adapted for such use in that, as hereinbefore stated, the possibility of leakage is practically eliminated.

From the above, it will be evident that our improved type of pipe coils for use in refrigeration systems furnish many advantages over the coils now in use. It will thus be seen that our arrangement makes possible the installation of a materially greater evaporating surface than is possible with the older forms of pipe coil. Further, by the use of the vertical pipes connecting the horizontal headers, an arrangement is provided whereby in case of breakage of any of the parts the system may be easily and completely drained of the ammonia gas, and with reference to the question of practical design, embodies advantages in ease of installation minimum possibility of breakage, and simplicity of installation.

Without further analysis, the foregoing will so fully reveal the gist of this invention that others can, by applying current knowledge, readily adapt it for various applications without omitting certain features that, from the standpoint of the prior art, fairly constitute essential characteristics of the generic or specific aspects of this invention and, therefore, such adaptations should and are intended to be comprehended within the meaning and range of equivalency of the following claims.

We claim:

1. In a refrigeration system, in combination with a freezing tank, a pipe coil comprising upper and lower horizontal headers and a plurality of pipe sections connected therewith and arranged substantially at right angles thereto, said sections being spaced from each other to permit an ice can to be interposed therebetween, said pipe sections comprising upper and lower horizontal headers and vertical connecting tubes.

2. In a refrigeration system, in combination with a freezing tank, a pipe coil comprising upper and lower horizontal headers positioned in the same vertical plane and extending centrally through said tank, and a plurality of pipe sections connected to said headers and arranged substantially at right angles thereto, said sections being spaced apart to permit an ice can to be interposed therebetween, and comprising upper and lower headers and a plurality of tubes connecting said last-named headers. 40
3. In a refrigeration system, in combination with a freezing tank, upper and lower horizontal headers positioned in the same vertical plane and extending centrally through said tank, a plurality of vertical tubes connecting said headers, and a plurality of pipe sections connected to said headers and extending on each side thereof, said sections being spaced from each other to permit an ice can to be interposed therebetween, each of said sections comprising upper and lower horizontal headers and vertical connecting tubes. 45
4. In a refrigeration system, in combination with a freezing tank, a pipe coil comprising upper and lower horizontal headers and a plurality of pipe sections connected therewith and arranged substantially at right angles thereto, said sections being spaced from each other to permit an ice can to be interposed therebetween, said pipe sections comprising upper and lower horizontal headers and parallel connecting tubes, all of the joints between said headers and connecting tubes being welded thereby to eliminate leakage therebetween. 50
5. In an ice making system, in combination, a tank adapted to contain a freezing medium therein, upper and lower horizontal headers within said tank and extending centrally with relation thereto adapted to contain a liquid refrigerant to abstract heat upon evaporation thereof from said cooling medium, parallel, vertical pipes connecting said headers, and a plurality of pipe sections connected to said headers, and positioned substantially at right angles thereto, said sections being spaced apart to permit an ice can to be interposed therebetween, said sections comprising upper and lower horizontal headers and vertical connecting pipes, all of the joints between said headers and connecting pipes being welded to thereby eliminate leakage therebetween. 55
6. In an ice making system, in combination, a tank adapted to contain a freezing medium therein, upper and lower horizontal headers in the same vertical plane within said tank and extending centrally with relation thereto adapted to contain a liquid refrigerant to abstract heat upon evaporation thereof from said cooling medium, parallel pipes connecting said headers, and a plurality of pipe sections connected to said headers, and positioned substantially at right angles thereto, said sections being spaced apart to permit an ice can to be interposed therebetween, said sections comprising upper and lower horizontal headers and connecting pipes, all of said headers and pipes being welded at their connecting joints. 60

Signed at San Antonio, Texas, this 2nd day of April, 1923.

MARK. F. POSTLEWAITE.

TROY V. LAWSON.
